UNITED STATES PATENT OFFICE.

JAMES A. KOLBY, LOUIS P. LARSON, AND CHRISTIAN P. NIELSEN, OF EPHRAIM, UTAH,
ASSIGNORS TO KOLBY WHEEL COMPANY, OF SALT LAKE CITY, UTAH.

RESILIENT WHEEL.

1,302,177.

Specification of Letters Patent. Patented Apr. 29, 1919.

Application filed February 13, 1919. Serial No. 276,775.

To all whom it may concern:

Be it known that we, JAMES A. KOLBY, LOUIS P. LARSON, and CHRISTIAN P. NIELSEN, citizens of the United States, residing 5 at Ephraim, in the county of Sanpete and State of Utah, have invented certain new and useful Improvements in Resilient Wheels; and we do declare the following to be a full, clear, and exact description of the 10 invention, such as will enable others skilled in the art to which it appertains to make and use the same.

Our invention has for its principal object to so improve upon the construction covered 15 by our United States Patent No. 1,286,348 of December 3rd, 1918, as to provide a more rigid and durable wheel which may be manufactured at less cost than the patented device.

20 In carrying out the above end, further objects are to provide for anchoring the spoke guides in a novel manner; to stamp the two side disks in identically the same manner so that any disk will fit either the 25 inner or the outer side of the wheel; to so shape the disks and secure them together as to effectively stiffen the wheel against lateral listing and to form holding means for the outer spoke guides; to provide means for 30 preventing chafing of the spring steel band against the rim sections; and to guard the air tube against injury by the shoes on the inner ends of the spokes.

35 In carrying the above objects into effect, we make use of a number of novel features of construction herein fully described and claimed, and shown in the accompanying drawings.

40 Figure 1 is a side elevation of the wheel applied to an automobile.

Fig. 2 is a vertical transverse section on the plane indicated by the line 2—2 of Fig. 1.

45 Fig. 3 is a detail sectional view on the plane indicated by the line 3—3 of Fig. 2.

Figs. 4 and 5 are detail sections cut transversely through several of the spokes and adjacent parts, as viewed on the planes of the lines 4—4 and 5—5.

50 Fig. 6 is a sectional perspective view showing a portion of one of the side disks.

In the drawing above briefly described, the numeral 1 designates a hub member having an annular outstanding flange 2 on its 55 inner end, in turn provided with a lateral

circumferential flange 3 concentric with the hub. The flange 2 may also carry the brake drum 4, and the several parts 1, 2, 3, 4 are by preference cast in a single piece, peripheral flanges 5 being at the same time formed 60 on the flange 3, while circumferentially spaced openings 6 are formed through said flange, either during the casting operation or later, by drilling. Sheet steel sleeves 7 are frictionally held in the openings 6 and 65 contain wear-resisting bushings 8 preferably of fibrous material such as that used for brake linings upon automobiles. This material is commonly reinforced with closely woven copper or brass wire and it, 70 therefore, resists wear to the maximum, at the same time being sufficiently porous to contain lubricating oil for the spokes 9 which pass slidably through the bushings. Both ends of the sleeves 7 are curved in- 75 wardly at 10 around the ends of the bushings 8 to retain the latter in place and at the same time to reduce the ends of said sleeves so that either end thereof may be easily started into the openings 6 and then 80 completely inserted into such openings by means of a hydraulic or other suitable press. By thus inserting the sleeves and their bushings, they will be frictionally held in place yet may be rather easily removed and replaced when necessary. We here direct particular attention to the manifold function of inwardly bending the sleeve ends around the ends of the bushings 8. The sleeves in 85 question are of stamped metal construction and may be easily and cheaply manufactured, and by stamping their ends inwardly as shown, not only are the bushings held in said sleeves, but the latter are reversible so that in assembling, it is not necessary to 90 identify the end to be forced into the opening. These are highly important features from a manufacturing standpoint and they likewise assist materially in providing a wheel which will be of exceptional dura- 95 bility. This is due to the fact that the bushings 8 may be impregnated with oil or grease to reduce friction and wear, and the nature of the material of which the bushings are constructed, will resist wear to the 100 maximum.

Coacting with the sleeves 7 and bushings 8, in guiding the spokes 9, are outer sleeves 7^a carrying bushings 8^a, the construction of these parts being identical with the corre- 105

sponding parts above described; and their size is the same to facilitate manufacture and assembling. The sleeves 7^a are carried by a pair of spoke bracing, side disks 11 which are of the same size and shape so that they may be interchangeably used in assembling. The inner edges of the disks 11 are riveted or otherwise secured at 12 to the flanges 5; and between the spokes 9, said 10 disks are stamped inwardly at 13, thus providing hollow spoke receiving ribs 14, the inwardly stamped portions 13 being riveted or otherwise secured together at 15 so as to form an extremely rigid structure 15 which will not yield laterally to any appreciable extent. The outer ends of the hollow ribs 14 receive the sleeves 7^a snugly therein and in order to hold said sleeve against displacement, the ribs are by preference 20 stamped inwardly around the curved ends thereof as indicated at 16. The inward stamp of the ribs is sufficient only to prevent endwise sliding of the sleeves 7^a and does not prevent insertion of said sleeves by 25 hydraulic or other pressure.

Overlapping the inner edge of the outermost disk 11 and secured to the free edge of the flange 3 by cap screws or the like 17, is a removable side plate 18 having a central 30 opening through which the reduced outer end 19 of the member 1 projects, said side plate forming with the parts 1, 2, and 3, a casing for a pneumatic tube 20 which cushions the movement of the spokes 9. The 35 tube 20 may be provided with any preferred form of inflation valve 21 extending outwardly through the plate 18, and the central portion of this plate is preferably held against a shoulder 22 on the member 1, by 40 means of an appropriate hub cap 23, which may also, if desired, serve to secure the wheel upon the axle when said wheel is to be used as a driver. When the wheel is to be used on the front axle of a vehicle, any suitable 45 form of bearings will, of course, be provided in the hub for rotation upon the axle spindles.

The periphery of the tube 20 is provided with a protecting band 24 of felt or any 50 other preferred material, and the shoes 25 on the inner ends of the spokes 9 are equipped with sheets 26 of fabric or the like, resting against said band. The sheets 26 are by preference of greater size than the shoes 55 25 so that the edges of the latter are prevented from injuring the band 24 or the tube 20.

The outer ends of the spokes are suitably pivoted at 27 to channeled rim sections 27^a

within whose channels a spring metal band 60 28 is positioned, said band carrying a cushion tire 29 whose base is held by the side flanges of the rim sections. Chafing and unnecessary wear of the band 28 and the rim sections 27, are prevented by an additional 65 band 30 of felt, brake lining material or the like, interposed between the bottoms of the channels of said rim sections and the band 28.

By constructing the wheel in the manner 70 shown and described, we are enabled to manufacture more easily and at less expense than we could produce the patented wheel above referred to, and at the same time the device is rendered more durable and rigid. 75 Since probably the best results are obtained from the details disclosed, they may well be followed, but within the scope of the invention as claimed, numerous minor changes 80 may well be made.

We claim:

1. In a resilient wheel, a hub structure, a plurality of sliding spokes radiating from said hub structure and carrying a rim, and cushioning means for said spokes; together 85 with a pair of spoke-bracing disks secured to said hub structure on opposite sides of said spokes, said disks being inwardly stamped between the spokes, thus forming hollow ribs receiving said spokes, said inwardly stamped portions being secured together, spoke-receiving, metal sleeves in the outer ends of said ribs, and wear-resisting bushings in said sleeves, both ends of said sleeves being inwardly curved around the 90 ends of the bushings to retain them in place and to allow either end of the sleeves to be inserted first into the ribs, said ribs being inwardly stamped around the curved ends of said sleeves to retain the latter against 95 removal.

2. In a resilient wheel, a hub having a circumferential flange provided with spaced openings, frictionally held, metal sleeves in said openings having both of their ends 10 curved inwardly to the same extent to allow either end of said sleeves to be inserted first, wear-resisting bushings in said sleeves and retained therein by said inwardly curved ends thereof, spokes sliding through said 11 bushings, a rim to which said spokes are attached, and cushioning means for said spokes.

In testimony whereof we have hereunto set our hands.

JAMES A. KOLBY.
LOUIS P. LARSON.
CHRISTIAN P. NIELSEN.
